UNITED STATES PATENT OFFICE.

LYMAN S. HOLMES, OF SCHOHARIE, NEW YORK.

ENGINE.

SPECIFICATION forming part of Letters Patent No. 660,160, dated October 23, 1900.

Application filed February 5, 1900. Serial No. 4,037. (No model.)

To all whom it may concern:

Be it known that I, LYMAN S. HOLMES, a citizen of the United States, residing at Schoharie, county of Schoharie, State of New York, have invented certain new and useful Improvements in Engines; and I do hereby declare the following to be a full, clear, and exact description of the invention, such as will enable others skilled in the art to which it appertains to make and use the same.

My invention relates to certain new and useful improvements in engines wherein two pistons located one within the other and having paths of movements transverse to each other are operatively connected to the shaft, said pistons working within cylinders the inner one of which exhausts directly into the outer through ports leading through the walls thereof from opposite sides of the engine-shaft. The construction embodies mechanism for reversing the engine at the will of the operator and also automatic cut-off mechanism of a simple and effective character.

In the accompanying drawings, Figure 1 represents a front elevation of an engine embodying my invention. Fig. 2 represents a top plan view thereof. Fig. 3 represents an elevation at right angles with respect to Fig. 1. Fig. 4 represents a section on the line 4 4 of Fig. 2. Fig. 5 represents a partial section on the line 5 5 of Fig. 4. Fig. 6 represents an exterior view of the inner cylinder. Fig. 7 represents a top plan view showing the reversing-gear for the upper part of the inner cylinder. Fig. 8 represents a bottom plan view showing the lower part of the reversing-gear for the inner cylinder. Figs. 9 and 10 represent sectional views on the lines 9 9 of Fig. 5 and 10 10 of Fig. 9, respectively.

Similar letters of reference indicate similar parts throughout the several views.

Referring to the drawings, A indicates the power-shaft of the engine, and B indicates the main engine-cylinder, the latter being formed in two parts bolted together and having the exhaust-ports *a b* governed by the cut-offs *c d*, with their stems *e f* joined by links *g h* with a connecting-rod *i*.

Within the cylinder B is fitted the main piston, consisting of the disks *j k*, connected by the cylinder C, which cylinder is slotted at *l*, (see Fig. 4,) so as to permit the vertical

reciprocation of the piston. The cylinder C is provided with cylinder-heads *m m'*, having ports *n n'*, which register continuously with 55 passages leading from the supply or distributing chests *o o'*, said chests containing the valves *p p'*, which control the supply of steam, compressed air, or other motive fluid to the engine. The stems *r r'* of the valves *p p'* are 60 connected by short links and connecting-rod *q* with an eccentric *w²* upon the engine-shaft A, as indicated, whereby they are adapted to open and close respectively and relatively, as desired. The steam or other motive fluid referred to is supplied primarily through the inlet-pipe *s*, which enters the valve-box D, containing a shiftable valve *t*, (indicated by dotted lines in Fig. 2 and by full lines in Fig. 4,) so that by shifting said valve the motive 65 fluid will be directed into either the pipe *x* or the pipe *x'*, as the case may be. To this end the valve is provided with an operating-arm *u*, connected by the link *u'* with the arm *v*, fixed upon a rock-shaft *v'*, having an operating-handle *w*. The operating-arm is provided with a locking-pawl engaging in slots of the segment *w'* at opposite ends of the throw of said arm, so as to lock and hold it in the adjustment chosen. It will be noted that while 80 one of the pipes *x x'* is supplying the motive fluid to the distributing-chests *o o'* the other pipe conveys the exhaust to the valve-box D, from which it discharges by a single conduit *y* into the common exhaust-pipe F.

Within the inner cylinder C is located the inner piston, consisting of the heads *z z'*, connected together by the partition *b²*, which has a central opening within which fits a crank *z²* of the shaft A, suitable roller-bearings *z³* 90 being provided to reduce friction. Upon the shaft A are also mounted the eccentrics *c² d²*, operating the rods *e² f²*, which are connected at their upper ends by a slotted link *g²*, engaging with a pin *h²*, extending from the connecting-rod *i*. By reason of this construction and arrangement the exhaust-valves *a b* are actuated at appropriate intervals. The slotted link *g²* is connected by a link *k²* with the reversing-lever *w*, so as to shift the cut-off valves with respect to each other when the engine is to be reversed, as hereinafter set forth.

The inner cylinder exhausts into the outer

cylinder through ports provided for the purpose in the heads j k . These ports are provided with valves for opening and closing them. The valves n^2 n^3 are pivoted at m^4 m^5 5 to the head j and govern the ports m^2 m^3 . They are connected by a bar o^2 , which is actuated by an arm o^3 , having a rectangular or polygonal slot through which passes freely the corresponding rectangular or polygonal 10 stem or blade o^4 , rigidly secured to the reversing valve t , so as to oscillate therewith. The blade o^4 does not partake of the reciprocating movement of the outer piston, but fits free within a slot therein, the arrangement 15 being such that the arm o^3 , moving with the piston to which it is attached, plays freely up and down upon the blade o^4 , while turning with said blade when the latter is oscillated with the reversing valve. A link p^2 connects 20 the bar o^2 with an arm p^3 , fixed to a vertical rod p^4 , which passes entirely through the outer piston and carries at its lower end an arm p^5 , pivotally connected to a bar p^6 . To the bar p^6 are attached valves t^2 t^3 , pivoted to 25 the head k at t^4 t^5 , said valves governing the ports s^3 s^2 , respectively. It will be apparent that an oscillation of the reversing valve t in one direction will cause the one pair of ports m^2 s^2 to open and the other pair of ports m^3 30 s^3 to close, as indicated in Figs. 4, 7, and 8, whereas the oscillation of the reversing valve t in the opposite direction will cause the pair of ports m^2 s^2 to close and the other pair of ports m^3 s^3 to open. It will also be apparent 35 that the same reversing-lever w effects simultaneously the reversal of the valve t , the cut-offs c d , and the reversing valves just referred to.

On referring to Figs. 9 and 10 it will be 40 seen that the partition b^2 , joining the heads z z' , is provided on opposite edges with recesses z^5 z^5 , having inclined cam-surfaces z^4 z^4 , and that in these recesses there are located bars b^3 b^3 , having similar cam-surfaces. Between 45 the edges of the partition b^2 and the inner wall of the cylinder C there are arranged antifriction-rollers r^2 r^2 , said rollers being located and confined within the recesses z^5 . The object of these rollers is of course 50 to avoid friction, and the cam-bars are to take up slack as required, for which purpose they are connected to the heads z z' by means of set-screws s^3 S^3 .

It will be observed that the piston-heads 55 j k m m' are provided with steam-tight packing w^3 , as shown, and, furthermore, that the heads z z' of the inner cylinder are similarly packed at v^5 . The extent of contact of the heads m m' with the walls of the outer cylinder 60 is correspondingly diminished, as will be plainly seen on reference to Fig. 5, the friction being furthermore decreased by reason of the fact that the steam passes freely through the openings n n' into the space beyond. 65

The operation of the engine will be readily understood. Steam, compressed air, or other

motive fluid being admitted to the valve-box t will when the parts are in the adjustment 70 illustrated in the drawings pass, as indicated by the arrows, through the pipe x to the distributing-chests o o' . Entering through the valve p into the cylinder C the motive fluid will advance the inner piston toward the right, carrying with it the partition b^2 and 75 effecting a partial revolution of the power-shaft A . When the partition b^2 has been carried past the dead-point, the motive fluid will issue through the port m^2 and will act expansively in the upper part of the outer cylinder, thereby forcing the outer piston downward and continuing the revolution of the shaft. When the outer piston has reached the limit of its downward movement, the valves p p' and also the cut-offs c d attain 80 relatively reverse positions, whereupon the motive fluid enters through the valve p' and drives the inner piston toward the right, causing the shaft to make the third quarter of its revolution. When the piston passes the port s^2 , the motive fluid issues through said port and is used expansively to drive the outer piston upwardly, thereby completing the cycle. From what has been said hereinbefore 85 as to the construction and mode of operation 90 of the reversing-gear it will be evident that in order to reverse the engine it is merely necessary to release the hand-lever w from its initial position and to draw it over the segment w' until it reaches the limit of its 95 throw. Auxiliary pipes (not shown in the drawings) connect the larger and smaller cylinders with the motive agent, said pipes being fitted with appropriate stop-cocks and are 100 adapted to be used for the purpose of starting the motor should it be stopped at a point 105 where the supply of the said agent is cut off.

Having thus described my invention, what I claim as new, and desire to secure by Letters Patent, is—

1. An engine, comprising a shaft, two pistons located one within the other and having paths of movement transverse to each other, said pistons being operatively connected to the shaft, cylinders within which the pistons move, the inner cylinder being provided with two pairs of ports, each coöperating pair leading through the walls of the outer cylinder from opposite sides of the engine-shaft, and reversing valves and valve-gear for closing one pair of ports and opening the other; substantially as described.

2. An engine, comprising a shaft, two pistons located one within the other and having paths of movement transverse to each other, 125 said pistons being operatively connected to the shaft, cylinders within which the pistons move, the inner cylinder being provided with two pairs of ports, each coöperating pair leading through the walls of the outer cylinder 130 from opposite sides of the engine-shaft, and reversing valves and valve-gear for closing one pair of ports and opening the other, said reversing valves and valve-gear comprising

two pairs of valves connected to move simultaneously and an actuating stem or rod; substantially as described.

3. An engine, comprising a shaft, two pistons located one within the other and having paths of movement transverse to each other, said pistons being operatively connected to the shaft, cylinders within which the pistons move, the inner cylinder exhausting into the outer, and the outer cylinder exhausting into the air, valves governing said exhausts, admission-ports for the inner cylinder, valves governing said admission-ports, a main distributing-box governing the flow of motive fluid to said admission-ports, a reversing valve within said box and a reversing-lever operatively connected to reverse said valves; substantially as described.

4. An engine, comprising a shaft, two pistons located one within the other and having paths of movement transverse to each other, said pistons being operatively connected to the shaft, cylinders within which the pistons move, admission-ports at opposite ends of the inner cylinder, supply-chests for said ports, a main distributing-box governing the flow of motive fluid to said admission-ports, said box having pipe connections with said chests, a reversing valve within said box, and a reversing-lever operatively connected to reverse said valve; substantially as described.

5. An engine, comprising a shaft, two pistons located one within the other and having paths of movement transverse to each other, said pistons being operatively connected to the shaft, cylinders within which the pistons move, admission-ports at opposite ends of the inner cylinder, exhaust-ports at opposite ends of the outer cylinder, valves for said admission and exhaust ports, and eccentrics on the

engine-shaft for operating said valves; substantially as described.

6. An engine, comprising a shaft, two pistons located one within the other and having paths of movement transverse to each other, 45 said pistons being operatively connected to the shaft, cylinders within which the pistons move, admission-ports at opposite ends of the inner cylinder, supply-chests for said ports, a main distributing-box governing the supply of motive fluid through said chests and ports to the inner cylinder and receiving the partial exhaust therefrom, an exhaust-pipe into which the exhaust received by the distributing-box discharges, and a reversing 50 valve for said box; substantially as described.

7. An engine, comprising a shaft, two pistons located one within the other and having paths of movement transverse to each other, the inner piston being connected to a crank 60 on the shaft by means of a web of the inner piston, said web being provided with means to permit of its adjustment to take up wear; substantially as described.

8. An engine, comprising a shaft, two pistons located one within the other and having paths of movement transverse to each other, said pistons being operatively connected to the shaft, and cylinders within which the pistons move, the inner cylinder being adapted 65 to exhaust directly into the outer cylinder through ports leading through the walls of the inner cylinder from opposite sides of the engine-shaft, substantially as described.

In testimony whereof I affix my signature 75 in presence of two witnesses.
